DESIGN FOR A JAR.

40,953.

Specification for Design.

Patented Oct. 25, 1910.

Application filed July 16, 1910. Serial No. 572,386. Term of patent 14 years.

To all whom it may concern:

Be it known that I, EMMA R. LEE THAYER, a citizen of the United States, and resident of Hastings-upon-Hudson, county of Westchester, State of New York, have invented a new, original, and ornamental Design for a Jar, of which the following is a specification.

Reference is to be had to the accompanying drawing in which—

Figure 1 is an elevation of a jar showing my new design and Fig. 2 is a plan view thereof.

The design which appears on each face of the jar comprises a central substantially

elliptical raised panel on which is produced in relief a fleur de lis. Columns having curved sides, rectangular upper portions and their lower ends terminating in a leaf design are located at each corner of the jar and project beyond the body of the jar to form supports.

I claim:

The ornamental design for a jar as shown and described.

EMMA R. LEE THAYER.
